OPTICAL SMOKE DETECTOR

Clarence Neel Cahusac, Newark, and Frank B. Allen, Towaco, N. J., assignors to C-O-Two Fire Equipment Company, Newark, N. J., a corporation of Delaware

Application November 14, 1949, Serial No. 126,966

1 Claim. (Cl. 88—14)

1

This invention relates to smoke detectors and, more particularly, to a smoke detector for use on a vehicle such as an airplane in which the detector preferably is mounted on the instrument panel.

Heretofore, visual smoke detectors have been provided for shipboard installation. However, such apparatus have been large and cumbersome and unsuited for use in vehicles such as an airplane in which space and weight is limited. Smoke detectors have also been provided of the audible type in which an alarm is given when smoke varies the light on a photoelectric element initiating an alarm. While generally satisfactory, it is possible for the audible smoke detector to become defective and cause an alarm signal to be given when in fact no smoke is present. In this case serious harm might be done if a fire extinguishing agent were to be discharged into the engines or other parts of the plane.

The present invention aims to overcome the foregoing difficulties and disadvantages by providing a visual smoke detector which is light in weight and compact in size.

Another object of the invention is to provide a smoke detector which is simple and economical in manufacture, efficient in operation and durable in use.

In accordance with the invention a smoke detector is provided which may be mounted on the instrument panel of the vehicle such as an airplane. Air to be tested for smoke is caused to flow through the detector into a beam of light. In the event smoke is present in the air the smoke particles reflect light into the range of sight of the pilot thereby attracting attention and also providing a positive check indication of smoke in the event an alarm signal has been given by an audible smoke detector. The detector casing is so constructed that the beam of light normally is not visible from the viewing opening of the detector, the light being visible only when reflected from the particles of smoke.

A smoke detector in accordance with the invention is advantageous not only in detecting smoke but also for indicating the absence of smoke after the fire has been extinguished.

Other objects and advantages of the invention will be apparent from the following description and from the accompanying drawings which show, by way of example, embodiments of the invention.

In the drawings:

Figure 1 is a front view of a smoke detector constructed in accordance with the invention.

Figure 2 is a rear view of the smoke detector.

Figure 3 is a plan view of the smoke detector with its top cover removed.

Figure 4 is a vertical longitudinal sectional view of the smoke detector taken along the line 4—4 of Figure 3.

Figure 5 is a vertical longitudinal sectional

2

view of the smoke detector taken along the line 5—5 of Figure 3.

Figure 6 is a vertical transverse sectional view of the smoke detector taken along the line 6—6 of Figure 4.

Figure 7 is a sectional view corresponding to Figure 4 of another embodiment of the smoke detector in accordance with the invention.

Figure 8 is a plan view of the smoke detector shown in Figure 7.

Figure 9 is a front view of the smoke detector shown in Figure 7.

Referring to the drawings there is shown a smoke detector 1 in accordance with the invention. In the embodiment shown in the drawings the smoke detector is made with two testing compartments 2, each adapted to be connected by piping (not shown) to one or more compartments of a vehicle or other space of a structure to be supervised for the presence of smoke. Suitable means such as a suction pump may be used to circulate air from the compartment through the smoke detector and may be connected in the piping at any desired location. The smoke detector 1 includes a housing 4 enclosing a pair of light sources 6 each adapted to project a beam of light through a lens 8 into one of the smoke detecting compartments 2. Viewing windows 10 are provided for each of the smoke detecting compartments 2.

The housing 4 may be made of any suitable material, preferably light in weight, and may be molded or cast if desired. Space is provided in the housing 4 for the pair of testing compartments 2 positioned side by side and separated by a partition 11. Another partition 12 separates the testing compartments 2 from a space 14 for the light sources 6. Still another partition 16 abutting against the partition 12 provides a space or compartment 18 for electrical connection means. An inlet passage for each of the smoke testing compartments 2 is made by forming a passage 22 through a thickened portion of the housing 4 and entering the smoke detecting compartment 2 as indicated at 24. An outlet for the testing compartments 2 is provided at 26 into a passage 28 extending through the partition 12 in fluid communication with a second passage 30 through the partition 16 and through a third passage 32 in a thickened portion of the bottom of the housing 4. In an equivalent construction the outlet passage might be positioned in the lower edge of the partition 12 adjacent to the bottom of the casing or in a thickened portion of the bottom of the casing. Usual connection fittings 34 are provided to connect piping to the smoke detector housing.

The light source 6 is preferably an electric bulb carried in a socket 38 with terminals 40 connected by wires 42 to a disconnecting socket 44 secured in position in an opening in the housing 4 in any suitable manner such as by screws 46 extending through openings in the housing into

threaded apertures in the disconnecting sockets.

The lens 8 is mounted in an opening in the partition 12 and secured in position by the lens retaining member 48 threadedly engaged with the wall of the opening.

The viewing members 10 are positioned on the front of the smoke detector. Frames 50 of the windows 10 each have an annular shoulder 52 against which is positioned the viewing window transparent material 54 made of glass or plastic, cushioned by gaskets 56 and held in position by the ring nut 58 threadedly engaged with the inner surface of the frame. Baffle members 60 and 62 are each secured to the partition 11 as by screws 64 and have openings 66 and 68 therein providing an angle of sight view across the path of a beam of light projected from the light bulb 6 through the lens 8 into the detecting compartment 2. Any equivalent baffle means may be provided, such as the use of strips extending inwardly from the wall of the casing and arranged to provide the viewing openings or "apertured baffle means."

The openings 66 and 68 in the baffle members 60 and 62 are so arranged as to prevent extraneous rays of light from the light compartment from escaping into the range of sight of the operator of the vehicle in order to prevent eye strain and loss of "night vision." In order to absorb extraneous rays of light within the detecting compartments 2 the inner surfaces thereof are covered with a light absorbing material such as carpet pile 70, a spot being burned in the pile of the fabric as indicated at 72 to provide a pocket at the focal point of the rays of light projected by the lens 8. The smoke detector housing 4 is closed on its top, bottom, and side walls, and on its rear by thin cover plates 74 secured in position by screws or the like 76 extending through apertures in the cover plates to engage in screw holes in the body of the housing 4.

The front end of the housing is closed by a decorative cover plate 77 having an aperture approximately in the center thereof to receive a lug 78 extending from the housing 4 and engaged by a conventional slide fastener 80. The outer end of the lug 78 is made with an annular groove therein for engagement by the slide fastener to provide for the quick and easy removal of the cover plate for an inspection of the interior of the smoke detector or to replace the electric bulbs 6. The cover plate 77 is apertured to provide a view through the windows 10 in alignment with the openings 66 and 68 of the baffle members 60 and 62.

In order that a visual indication may be had as to the operability of the electric bulbs 6, sight openings are provided in the cover plate 77 as indicated at 82 and each are backed by a small piece of semi-transparent material 84 to permit the passage of only a small amount of light from the lamp bulb.

In Figures 7 through 9 another embodiment of the invention is illustrated in which corresponding parts are designated by the same reference numbers as in Figures 1 through 6 with the addition of 100. The smoke detector 101 differs principally from the smoke detector 1 in having a transparent window or plate 186, covering substantially the front face of the detector, and in this form of the invention the partition 112 at its front end 188 is turned upwardly to abut against the top corner of the casing. A passage 190 is formed in the partition 188 for light to pass through the semi-transparent ma-

terial 184 to indicate the operability of the lamp bulb 106. In the embodiment shown the window 186 is spaced as indicated at 190 from the front wall 191 of the detecting compartment 102. If preferred, a barrier might be placed in the space 190 between the front wall 191 of the detecting compartment and the window 186 to entirely isolate each compartment from the other. However, it has been found unnecessary to use such a partition or barrier as the smoke which may be present in either of the detecting compartments is evacuated through the outlet 126 without entering the space. This embodiment of the invention is advantageous in that a smoke detector is provided having a transparent face adapted to conform in size and appearance to the other instruments on the panel.

While the invention has been described and illustrated with reference to specific embodiments thereof, it will be understood that other embodiments may be resorted to or changes made therein without departing from the invention. Therefore, the form of the invention set out above should be considered as illustrative and not as limiting the scope of the following claim.

We claim:

A smoke detector for use on the instrument board of a vehicle, the detector comprising a casing of elongated shape and adapted to fit one of the usual instrument openings on the control board, a longitudinally extending partition for the front portion of the casing defining a light source compartment and a detecting compartment positioned side-by-side, a light source in the light compartment, lens means in the partition to project a beam of light into the detecting compartment, a transversely extending partition abutting the longitudinally extending partition and providing the rear end walls for the light and detecting compartments and defining a front wall for a wire connection compartment positioned in the rear of said light and detecting compartments for connection of wires between the lamp and the rear wall of the casing, means providing an inlet and an outlet for fluid to be tested for smoke terminating on the rear wall of the casing, said inlet means providing fluid communication to the detecting compartment, transparent viewing means providing a front wall for the detecting compartment, apertured baffle means between the transparent wall and the detecting compartment to restrict the angle of view approximately transversely of the beam of light, and means providing a passageway in the transversely and longitudinally extending partition walls to lead the smoke from the detecting compartment to the outlet on the rear wall, whereby the connecting fittings for the fluid inlet and outlet and for the electrical connections are accessible on the rear wall of the casing.
